UNITED STATES PATENT OFFICE.

JOHN L. ILES AND JOHN T. ILES, OF MAGNOLIA SPRINGS, ALABAMA.

APPARATUS FOR AUTOMATICALLY CONTROLLING THE HEADLIGHTS OF AUTOMOBILES.

Application filed September 27, 1922. Serial No. 590,843.

To all whom it may concern:

Be it known that we, JOHN L. ILES and JOHN T. ILES, citizens of the United States, both residing at Magnolia Springs, in the county of Baldwin and State of Alabama, have invented certain new and useful Improvements in Apparatus for Automatically Controlling the Headlights of Automobiles; and we do hereby declare the following to be a full, clear, and exact description of the invention, such as will enable others skilled in the art to which it appertains to make and use the same.

The present invention relates to improvements in apparatus for automatically controlling the headlights of automobiles in which the lights are of a dirigible character adapted to turn with the steering movement of the vehicle for the purpose of illuminating the road at sharp curves and at corners where fixed lights direct the beams only to one side leaving the major portion of the roadway in total darkness.

It is an object of the invention to accomplish this movement of the lamps simply and by inexpensive parts which will not add materially to the present front construction of vehicles, and particularly the invention aims to avoid any rattling or vibration in the lamps or adjoining parts to the end that the movement may be accomplished noiselessly and effectively.

With the foregoing and other objects in view, the invention will be more fully described hereinafter, and will be more particularly pointed out in the claim appended hereto.

In the drawings, wherein like symbols refer to like or corresponding parts throughout the several views,

Figure 1 is a top plan view of one of the lamps showing the improved connection.

Figure 2 is a side view of the same.

Figure 3 is a front view thereof.

Figure 4 is a section taken on the line 4—4 in Figure 5.

Figure 5 is a vertical section through the lamp bearing and,

Figure 6 is a perspective view of a bearing cone.

Referring more particularly to the drawings 1 designates the usual automobile head-lamp supported upon the post 2 and 3 designates a radiator or other portion of the vehicle indicated in dotted lines in Figure 3 to

which the bracket 4 is attached carrying the head-lamp. The steering cross-rod is represented at 5 and moves transversely of the vehicle with the steering movement in a well known manner. The bracket 4 carries a bearing 6 perforated vertically to receive the bolt 7 which serves to hold in place the supporting frame for the lamp-post 2. This supporting frame involves a pair of rear parallel arms 8 and 9 projecting respectively above and below the bracket bearing 6 and also perforated to receive the bolt 7 which is provided with the spring washer 10 and nut 11 to bind these various parts tightly together.

The frame further consists of a vertical web 12 connecting the arms 8 and 9 and extending above the upper arm. Forwardly projecting arms 13 and 14 are also carried by the web 12 and are offset upwardly with respect to the rear arms as will be clear from Figures 2 and 5. These forward arms are also perforated to receive the lamp-post 2 downwardly therethrough. The perforation in the upper arm is preferably produced by a divided bearing in which the rear portion of the bearing is designated at 15 and is made in one piece with the upper arm 13 while the forward portion of the bearing section 16 fits upon the outside of the post 2. The bearing sections are provided with lateral ears 17 and 18 perforated to receive the bolts 19 which support the outer section 16, the bolts being provided with spring lock washers 20 and with nuts 21. The heads of the bolts engage the ends of a flat spring 22 which bears intermediately against the central portion of the outer bearing section 16 urging this bearing section yieldably against the post 2. From time to time as wear occurs the nuts 21 may be tightened to set the spring and bearing up.

The bearing section 15 is also preferably recessed in order to receive the flat spring 23 or a number of shims, and these parts may be replaced, but it will be understood that due to the spring action of the outer bearing section wear will be automatically compensated for and the bearing will adapt itself to any changes in the lamp-post due to wear.

Now the lower perforated arm 14 is provided with a seat 24 preferably of brass in order to receive the bearing cone 25 which is affixed to the lower reduced or flattened end 110

of the post 2. This bearing cone 25 is provided initially with lugs 26 as shown in Figure 6 having flat inner faces to fit against the normally flat sides at the lower portion of the lamp-post and these lugs are preferably milled to the post. The weight of the lamp is thus sustained principally by the cone and the upper bearing forms a 10 steady support for the parts. Below the arm 14 is a washer 27 engaged by the coil spring 28 held in adjustable tension by a nut 29. The nut 29 cooperates with a lock nut 30 to hold therebetween the double perforated end portion 31 of the flat curved spring 32, which extends between the lamp post and the steering cross-rod 5. The connection at both ends of the spring 32 is made in any suitable manner such for instance as by the nuts upon the post 2 and the bolts 20 33 engaging the returned lower end of the spring upon the cross-rod. The connection and arrangement is such that as the cross-rod moves transversely it will swing the lamp-post 2 and thus turn the lamp 1 in the 25 direction in which the vehicle is being steered.

The lamp will thus be turned either to the right or to the left accordingly as the steering apparatus is moved in the one or other 30 direction and as a consequence the rays from the lamps will be directed in the same line as the front wheels of the vehicle and in rounding corners the illumination will spread to the inner side of the curve to enable the full view of the field in negotiating the turn. The construction of the frame 12 35 enables a secure purchase upon the lamp bracket and also affords a two-point support

for the lamp-post. The cone 25 substantially supports the lamp and post and it is held close against its seat by the action of the coil spring 28 which tends to draw the post 2 axially down. Consequently the bearing is automatically taken up as wear occurs. This wear of course will be slight and the upper arm 13 provides spring pressure against any later vibration so that the lamp is held substantially rigid while being capable of executing easily the movement to the right or left. 50

It is obvious that various changes and modifications may be made in the details of construction and design of the above specifically described embodiment of this invention without departing from the spirit thereof, such changes and modifications being restricted only by the scope of the following claim: 55

What is claimed is:

A head lamp having a post, a bracket 60 frame carried by the vehicle having upper and lower arms, said upper arm having a divided bearing engaging about the post, spring means to urge the bearing sections together upon the post, a flat spring embedded in one of the bearings and engaging said post, a cone bearing carried by the post and seating upon the lower arm, an adjustable spring for drawing the bearing means against said seat, a curved flat spring engaging tightly about the lower end of said steering post and having its other end affixed to the steering cross-rod, substantially as described. 65 70
